Inventor.
HENRY PETERSEN.

By *E. H. Bond*
Atty.

Patented Oct. 4, 1927.

UNITED STATES PATENT OFFICE.

HENRY PETERSEN, OF MOUNT AUBURN, IOWA.

CULTIVATOR.

Application filed July 30, 1925. Serial No. 47,022.

This invention relates to cultivators, and more particularly to that class of cultivators known in the art as "straddle-row" cultivators, and it has for its object, among others, to provide an improved construction based principally upon and designed as an improvement on the construction shown in Patent No. 1,510,524, granted to me October 7, 1924.

10 In this patent the outside beams are relatively fixed, that is, having no pivotal movement to or from the other beams. I have found from experience that this arrangement does not allow sufficient lateral movement of the pivoted inside beams next to the plant row, and to overcome this objection I provide the novel construction hereinafter described. The basic novel feature of the present construction provides in the pivoting 15 of the outside beam so that it is free for lateral movement, and in pivotally connecting said outside beam with the next adjacent beam and so on, whereby all beams are mounted to move in unison. The beams in 20 one form of the invention are mounted each upon its own individual or independent pivot and the inclined members connecting the same pivotally join each two adjacent beams. By this means the beams are 25 capable of opening or closing in fan-like fashion. This serves to give the inside beams more lateral movement and less lateral movement of the outside beams which 30 prevents the outside beams from coming in contact with the wheels. Furthermore, the 35 outside beam serves to limit the lateral movement of the other beams, while the separating of the beams enables me to cover all the ground and guards against none being 40 missed during the operation of the cultivator. The same result practically is obtained by mounting the two inside beams upon a common pivot and so connecting the 45 outside beam pivotally with the inside beams to give them pivotal movement laterally relative to but also in unison with the outside beam.

I aim further at improvements in the details of construction, facilitating the manufacture of the cultivator.

50 Other objects and advantages of the invention will hereinafter appear and the novel features thereof will be particularly pointed out in the appended claims.

55 The invention, in its preferred forms, is clearly illustrated in the accompanying

drawings which, with the numerals of reference marked thereon, form a part of this specification, and in which

Figure 1 is a side elevation of a cultivator 60 constructed in accordance with my present invention.

Figure 2 is a top plan thereof.

Figure 3 is a top plan showing one set of 65 beams and their connection, the same being shown in two positions, one by full lines and the other by dotted lines.

Figure 4 is a top plan with the tongue in 70 section, showing another form of arrangement and connection of the beams.

Figure 5 is a side elevation of Figure 4.

Figure 6 is a perspective detail showing the manner of mounting the pivot of the member connecting the beams.

Like numerals of reference indicate like 75 parts throughout the several views.

Referring to the drawings 1 designates the tongue, 2 the seat mounted on the cross member 3, and 4 the frame from the rear ends of which said cross member 3 is supported. 5 80 85 are the wheels, mounted on the spindles 6, carried by the arched axle 7, the latter being in the present instance secured to the under side of the transverse member 8. 9 are braces connecting the tongue with the angled ends 10 of the yoke 11, the transverse portion of which extends beneath the rear end of the tongue. All of these parts are well known or of any approved form of construction and of themselves form no part of 90 the present invention.

Referring first to Figures 1, 2 and 3, 12 designates the outside beam and 13 and 14 the inside beams of which latter there may be more or less as may be desired. The outside beam 12 is mounted upon a pivot 13 supported in the bracket or member 15 on the angled end 10 of the member 11, any suitable form of connection being employed as may be found most desirable. When two 100 inside beams are employed, such as 13 and 14 (see Fig. 3), the two are united in any suitable manner as, for instance, by being bolted to the casting or member 16 carrying the pivot 17, which is mounted in the member 15, all of which is clearly shown in Figure 3. In order that the outside beams 12 and the inside beams 13 and 14 may be joined so as to move in unison, I employ 105 the bar 18, one end of which is fastened to the outside beam 12 near its outer end, as seen at 19, and its other end connected as at 110

20, with one or the other inside beams 13 and 14 (see Fig. 3). This member 18 may be connected to either one of the beams 13 or 14 as may be found most desirable, the 5 result being practically the same, regardless of whichever one of the inside beams has connection with said member 18.

In order that the relative positions of the beams may be changed I mount the pivots 10 of the member 18 in a member 21 (see Fig. 6), which member slidably receives the member 18, the member 21 being designed to be secured in its adjusted position by suitable means, as the bolt 22 (see Fig. 6).

15 While the sets of beams at each side of the cultivator may be moved upon their pivots upward in any way, I have chosen to show in the present instance an efficient form comprising a rod 23 for each set of beams attached at its lower end in any suitable manner, as at 24, to one of the beams of a set and at the upper end in any suitable manner, as by hook and eye or the like, as shown at 25, to the member 26 which may be, for instance, of the two-arm type, as seen in Figure 2, the forward ends of which are pivotally mounted as at 27 in ears or the like 28, rising from the cross member 8, as shown clearly in Figure 2.

20 The operation will be readily understood upon reference to Figures 1, 2 and 3. The driver sits on the seat and with his feet may easily swing the beams inward or outward as circumstances may require to clear 35 the plants, the outer beams moving with the inner beams, the construction being such that it is not necessary for him to remove his hands from the reins. Any suitable form of foot rest 29 may be provided and the same

40 may be attached in any suitable manner to the beams, in the present instance being shown as mounted upon the brace member 30 connecting the beams 13 and 14, as seen clearly in Figure 3. It is evident, however, 45 that any other form of foot rest may be employed and attached in any other manner to any convenient part of the device. Attention is called to Figure 5 in which the foot rest 29 is shown and secured to the curved portion of one of the beams and having the opening 31 for the reception of the foot. This serves very efficiently as the foot rest, but any other form may be employed.

50 When it is desired to raise the beams from the ground the rod 23 and the member 26 is moved from the full line position, in Figure 1, to the dotted line position in said figure, when the beams and their earth-engaging members 32 will be elevated, as indicated by the dotted lines in said Figure 1.

55 The pressure of the foot of the driver tends to move the beams 12, 13 and 14 in unison either outward or inward as may be desired. As the beams are moved upon their

70 pivots the angle of the position of the member 18 is changed and this member 18 serves to limit the outward movement of the outer beam 12 so as to prevent its contact with the wheel, and by reason of the pivot connection of the member 18 with the outside beam and with the inner beams, the movement of the beams is accomplished with gradually lessening power or exertion as the beams are moved inward or into the 75 dotted line position in Figure 3. For ease of movement, that is, with the least exertion on the part of the driver, the foot rest is placed upon the inside beam and, in the present instance, between the two beams 13 80 and 14, as seen best in Figure 3.

85 As before stated, the angularly disposed members 18 pivotally connecting the inside and the outside beams permits of adjustment of the width of the beams or for any desired angle or movement of the folding of the beams by merely sliding the pivoted brace supports 21 lengthwise of the beams, tightening the bolt 22.

90 The lever-like folding of the beams permits of greater lateral movement of the inside beams with relatively less movement of the outside beam, thus avoiding unnecessary movement of the outside beam and rendering it much easier for the driver to 95 control.

95 In Figures 4 and 5 I have shown a slightly modified arrangement, but by means of which practically the same result is obtained.

100 In these views the outside beam 33 is mounted upon a pivot 34, the next adjacent inner beam 35 is mounted upon an individual pivot 36, while the next inner beam 37 is mounted upon its own individual pivot 38. 105 In this instance the pivots 34, 36 and 38 are all regulated by one member 39 having lugs 40 mounted upon the cross member 41 of the yoke 42. The beams 33, 35 and 37 may be connected each with its own pivot member 110 in any suitable manner and the outside beam 33 is connected with the beam 35 by inclined members or member 42, while the beam 35 is likewise connected with the other beam 37 by a similar member 43, shown clearly in 115 Figure 4, each end of the members 42 and 43 being mounted upon pivots 44 carried in the supports 21 provided with bolts 22, as seen in Figures 5 and 6, whereby the ends of the members 42 and 43 may be readily 120 slid upon the beams for the same purpose as above described, with reference to the form shown in Figures 1, 2 and 3. The foot rest 29 in this instance is secured to the innermost beam 37, as seen in Figure 4, to obtain greatest leverage and consequent ease of movement of the beams upon their pivots. In this form the beams can be readily moved inward or outward as occasion may require, and as will readily be seen by reference to 125 130

Figure 4, no ground will be missed in the operation of the device. The outermost beam is limited in its movement by reason of its pivoted connection with the next adjacent beam, and all three beams are simultaneously moved upon their pivots 34, 36 and 38. The dotted line position in Figure 4 readily indicates the manner in which these beams are moved, and the relative amount of movement of the three beams.

In this form as in the form shown in Figures 1, 2 and 3, the beams may be moved simultaneously up or down by means similar to that shown in Figures 1 and 2, or by any suitable or convenient means.

Modification in detail, proportion and relative arrangement of parts may be resorted to without departing from the spirit of the invention or sacrificing any of its advantages.

What is claimed as new is:

1. In a cultivator, a pivotally mounted outer beam, an independently mounted inner beam and a member slidably and adjustably mounted upon one of said beams, and a member disposed inclinedly angularly with relation to said beams and at one end pivotally mounted upon said slidable member and at the other end pivotally and slidably connected with the adjacent beam.
2. In a cultivator, a frame, a tongue, yokes, means connecting the angled ends of the yokes with the tongue, an outside beam mounted on the angled end of one of the

yokes, inner beams mounted on the yoke, and rearwardly and outwardly inclined members pivotally connecting the same and slidable along the beams with means for securing said members in any adjusted position lengthwise of said beams, whereby the movement of the beams is accomplished with gradually lessening power as the beams are moved inward.

3. In a cultivator, pivotally mounted beams arranged on both sides, members slidable along the beams, means for securing said members in any adjusted position lengthwise of said beams, and a bar pivotally connected to the members on separate beams.

4. In a cultivator, pivotally mounted beams arranged on both sides, members embracing the beams and slidable therealong, means for securing said members in any adjusted position lengthwise of said beams, and a bar pivotally connected to the members on separate beams.

5. In a cultivator, pivotally mounted beams arranged on both sides, members slidable along the beams, means passing through the upper part of said slidable members adapted to engage the said beams to secure said members in any adjusted position lengthwise of the beams, and a bar pivotally connected to the members on separate beams.

In testimony whereof I affix my signature.

HENRY PETERSEN.
